UNITED STATES PATENT OFFICE.

ANTON WILLIAM BALDER, OF PITTSBURG, CALIFORNIA, ASSIGNOR OF ONE-FOURTH
TO MARTIN W. DUNN, OF OAKLAND, CALIFORNIA.

TRUNK.

Application filed April 7, 1920. Serial No. 371,991.

To all whom it may concern:

Be it known that I, ANTON WILLIAM BALDER, a citizen of the United States, and a resident of Pittsburg, in the county of 5 Contra Costa and State of California, have invented certain new and useful Improvements in Trunks, of which the following is a specification.

My invention is an improvement in trunks, 10 and has for its object to provide a trunk especially adapted either for use as a trunk or as a dressing table or case, wherein the body of the trunk has supporting legs for supporting the trunk in elevated position, 15 the said legs being hinged to the body to fold up at the corners thereof, and the lid or cover and the legs have interchanging means for detachable connection therewith and clamping the legs in such position during 20 transportation, the arrangement being such that when not in use the legs will not interfere with the handling of the trunk, nor add to its bulkiness but will reinforce the corners of the trunk against injury.

25 In the drawings:-

Figure 1 is a top plan view of the improved trunk;

Figure 2 is a front view;

Figure 3 is an end view of the lid open;

30 Figure 4 is a perspective view of the upper end of the leg;

Figure 5 is a perspective view of the spring latch or catch;

Figure 6 is a sectional detail through one 35 of the catches; and

Figure 7 is a perspective view of the hinged connection of one of the legs.

In the present embodiment of the invention, the trunk which is of any usual or 40 desired construction, and of any dimensions, is composed of a body 1 and a lid or cover 2, which is hinged to the body, as indicated at 3 to open or close with respect to the body, and the body has the usual 45 handles 4.

A series of legs 5 is hinged to the body at the bottom thereof, each of said legs, as shown more particularly in Figures 4 and 7 being of any material and being rigidly 50 secured to or integral with plates 6 and 12 at its ends. Each of these plates 6 and 12 extends in a plane perpendicular to a portion of the legs, and fits closely between portions of the legs.

55 Each plate 6 carries two hinged lugs

spaced apart laterally from each other and adapted to receive between them a third lug 8 which is secured to a plate 9 held in a rabbet 10 in the under face of the trunk bottom. The lug 8 is so spaced from the 60 corner of the trunk that when the leg is swung up in the inoperative position, as shown in Figure 2, it will fit about the corners of the trunk forming a reinforcement for the corner. When the legs are un- 65 folded as shown in Figure 7, the lugs 7 will rest upon the trunk bottom on either side of the lug 8 forming a firm support for the legs.

When the legs are folded up about the cor- 70 ners of the trunk, mechanism is provided about the cover 2 for detachably engaging the upper end of the lug to hold it in place. A plate 13 is countersunk in the top of the cover at each corner and is held in place 75 by the screw or the like as shown, in the same manner as the plates 9 are held. Each of these plates 13 is provided with an opening 14 of polygonal outline, which is adapt- 80 ed to be engaged by a nut 15 on a resilient latch member or spring 16 held between the plate 13 and the top of the trunk cover, the plate and trunk cover being recessed to receive the latch, as shown in Figure 6. That face of the catch 15 which is outward is bevelled as shown, so that when the plate 12 is 85 moved inwardly on the plate 13 the catch or latch will be depressed. Ribs 18 are pro- 90 vided for each lug, the ribs being secured to the trunk in spaced relation, and in such 95 manner that the plate 12 may slip therebetween when the legs are folded in inoperative position.

It will be obvious that when the plate is 96 so slipped into place and the catch 15 is en- gaged with the opening 14, the plate 12 will be held from outward movement, and will be locked in place. In line with the open- 100 ing 14 each plate 12 is bevelled on its under face as shown at 19 for cooperating with the bevelled face of the catch to move the said catch downwardly when the leg is slipped into place.

In use, when travelling or when the trunk 105 is in storage, the legs are arranged as shown in Figures 1 and 2, being folded upon the corners of the body and connected with the cover. When it is desired to use the trunk as a dresser or to have the contents thereof easily accessible, the parts are arranged as 110

shown in Figure 3. The legs are folded down beneath the bottom as shown, the catches 15 being depressed to permit the release of the legs.

5 I claim:-

1. A trunk having hinged to the bottom thereof legs for supporting the trunk in elevated position, said legs being of angular material and connected with the trunk to 10 fold up and fit about the corners thereof to provide reinforcements for the said corners, the cover and legs having interengaging means for holding said legs in folded position.

- 15 2. A trunk having legs hinged to the bot-

tom thereof to turn down perpendicularly to the bottom or upwardly about the corners of the bottom, and means for detachably connecting the free ends of the legs to the top of the trunk, said means comprising 20 angular plates on the free ends of the legs adapted to lap and fit against the top of the trunk when the legs are folded, said plates having openings and the trunk top having spring latches for engaging the 25 openings, said latches being covered and concealed by the angular plates when in place.

ANTON WILLIAM BALDER.
